UNITED STATES PATENT OFFICE.

EDWIN B. LANGSDORF, OF NEW YORK, N. Y.

DESIGN FOR A MIRROR OR SIMILAR ARTICLE.

Application filed June 11, 1928. Serial No 27,072. Term of patent 3½ years.

To all whom it may concern:

Be it known that I, EDWIN B. LANGSDORF, a citizen of the United States, and a resident of the city of New York, in the county of New York and State of New York, have invented the new, original, and ornamental Design for a Mirror or Similar Article, of which the following is a specification.

Reference is had to the accompanying drawing, forming part thereof, wherein

I claim:

The ornamental design for a mirror or similar article substantially as shown.

EDWIN B. LANGSDORF.
